(57) CLAIM

The ornamental design for a portion of a scanner, as shown and described.

DESCRIPTION

FIG. 1 is a perspective view of a portion of a scanner;
FIG. 2 is a top plan view of a portion of a scanner;
FIG. 3 is a bottom plan view of a portion of a scanner;
FIG. 4 is a front elevation view of a portion of a scanner;
FIG. 5 is a rear elevation view of a portion of a scanner;
FIG. 6 is a left side elevation view of a portion of a scanner;
FIG. 7 is a right side elevation view of a portion of a scanner; and,
FIG. 8 is a cross sectional view of a portion of a scanner taken along lines 8—8 in FIG. 2.

The broken lines are shown in the views for illustrative purposes only and form no part of the claimed design.
